UNITED STATES PATENT OFFICE.

ROBERT W. SCARLETT, OF PHILADELPHIA, PENNSYLVANIA.

HEAT-INSULATED CONTAINER.

Application filed September 15, 1926. Serial No. 135,637.

This invention relates to a shipping container particularly adapted for the shipment of material which must be kept cold, such as ice cream, milk, cheese, butter, fish, candy or 5 the like.

The principal object of the invention is the provision of such a container which will be so constructed and so insulated that no ice or other refrigerant will be necessary to 10 maintain for reasonable periods of time, the temperature of the material shipped.

Other objects are the construction of such a device which will be cheap to manufacture, which will be waterproof both inside and 15 out, which will be of sturdy construction to withstand the abuse to which it is normally subjected, and which will be of a minimum bulk.

To this end the invention contemplates the provision of an outer casing of sturdy material, such material comprising for instance fibre. This material may be had in either sheet or tube form. Obviously a seamless tube or cylinder would be preferred although 25 this is not essential. An inner metal can or container is spaced from the outer casing by some good heat insulator, such as hair felt or the like, stitched between sheets of more or less waterproof material. The stitching 30 prevents the hair felt from settling or sagging while the container is in use. A wood rim surmounts the top edge of the can in a water tight manner, and inside the outer casing. The bottom of the can rests 35 upon a composite wood block also within the outer casing, and a flanged metal plate underlies the wood block. A covering of duck or fabric is then applied to the outer casing, passing over the top of the wood rim and 40 the flange of the bottom plate. This duck or fabric is then securely held in place by gluing to the fabric and by means of a top and bottom rim preferably of metal riveted or otherwise secured to the casing, which 45 serves not only to hold the duck, but acts as a reinforcement to the edges in use. A top of wood or other insulating material, made waterproof by covering with duck or fabric, rests on a ledge or shoulder in the wood rim. 50 This cover may have a gasket to aid in tightly closing the container, and also be provided with a spring arm entering slots in the top reinforcing ring to securely and tightly close the container.

The invention further consists in the novel construction, combination and arrangement

of parts hereinafter described and shown in the accompanying drawings, in which:

Figure 1 is an enlarged fragmentary sectional view showing the construction of one 60 form of my invention.

Figure 2 is a perspective of the complete container.

Referring now to this drawing, the outer container or casing of some strong and tough 65 material such as fiber is shown at 1, and is of more or less cylindrical shape. Within this casing is located a metal can 2, galvanized or not as desired or of a non-corrosive metal. This can is preferably made 70 water tight as by soldering or brazing the seams, as it is extremely desirable that the insulating material between casing 1 and can 2 be kept dry.

Can 2 is provided with a flanged upper 75 rim as at 3, to which may be attached in any convenient manner an extension 4 extending upwardly.

A wood rim 5 surmounts the flange 3 and fits snugly within the casing 1. A channel 6 in the bottom of the rim 5 is adapted to receive the vertical portion of the extension 4 which may then be packed with asphaltum 80 waterproofing material or the like. Thus no water or moisture can leak between the 85 rim 5 and can 2. The rim 5 is preferably made of wood because of its insulating qualities. A shoulder 7 is provided to receive the top, to be described hereinafter.

Between the casing 1 and can 2 I provide 90 insulating material composed for instance of hair felt 8 stitched between sheets 9 of more or less waterproof paper. I have found that two thin sheets of this insulating material 95 serve the purpose better than a single greater thickness. This sheet insulator has the advantage of being capable of being readily handled and cut to shape so that a tight and accurate fit can be secured. The vertical stitching prevents the hair felt 8 from 100 sagging between its sheets 9.

Directly beneath the bottom of the can 2 I provide a block of wood 10, preferably balsa, which block also extends out to the casing 1, the can 2 resting in a dished cavity in the block top. This centers the can and prevents accidental displacement. Balsa wood is comparatively soft, and therefore I find it necessary to reinforce the block 10 by a secondary block 11 of hard wood, 110 and to provide hard wood plugs 12 extending through the blocks 10. These plugs 12

and the block 11 therefore support the weight of the can 2 and take the wear from the softer balsa block 10.

5 A flanged plate 13 preferably of metal underlies the hard wood block 11 and serves as the bottom of the container.

10 Duck, fabric or the like 14 is now stretched over and glued to the casing 1 with waterproof glue, overlying the top of wood rim 5 and the flange on bottom plate 13. A top reinforcing ring 15 is now placed outside the duck and securely bolted, screwed or riveted as at 16 to the casing 1. In a similar manner, a reinforcing ring 17 securely holds duck, bottom plate and casing together.

15 A top is provided and consists of a block of insulating material such as balsa as at 18 covered with duck or fabric 19 which may be impregnated with paraffin or the like to render the same waterproof. A hard wood disc 20 overlies the balsa block 18 and a gasket 21 lies in a marginal recess. A rotatable spring arm is shown at 22 held by bolt 23. The gasket 21 rests on the shoulder 7 of the container wood rim 5 and the ends of spring arm 22 enter opposed cut outs in the top ring 15, so that the top is securely held in place.

20 It will be noted that this device as described is absolutely waterproof both inside and out, so that no moisture as either leakage or condensation can enter and damage the insulation.

25 Moreover, the wood rim 5 acts as a heat barrier between the metal reinforcing ring 15 and the can 2, so that heat cannot leak or be conducted into the can and its contents by this route.

30 The fact that there is, on the side of greater exposure of the can 2, a layer of duck or fabric, a sheet of fibre, four thick-

nesses of paper and two of hair felt, all of which are heat insulators, effectively prevents the transfer of heat into the container, 45 so that ice cream, milk, cheese, butter, fish, candy, or the like placed within the can 2 will keep in good condition for great lengths of time.

50 What I claim is:

1. A portable insulated shipper comprising an outer casing, an inner receptacle, insulation therebetween, a bottom secured to the outer casing, a support for the inner receptacle which likewise supports said insulation, a dished cavity therein to receive the inner receptacle, a wood rim with a channel in its lower face, an upwardly extending flange in the inner receptacle in said channel and packed with waterproof material and a removable top engaging said rim. 55

2. A portable insulated shipper comprising an outer casing, an inner metallic receptacle adapted to receive the material to be shipped, insulation between the sides of the casing and the metallic receptacle, a unitary piece of relatively soft insulation between the bottom of the metallic receptacle and the bottom of the casing, said relatively soft insulation extending between the sides of 60 the metallic receptacle and the sides of the casing, relatively rigid material underlying the bottom insulation, and relatively rigid material passing through the soft bottom insulation and in contact with the relatively hard material underlying the insulation and in contact with the bottom of the metallic container, an upper rim attached to the casing, and making a water tight connection with the metallic receptacle, and a 65 removable top engaging said rim. 70

75 In testimony whereof, I affix my signature.

ROBERT W. SCARLETT.
